UNITED STATES PATENT OFFICE

WILLIAM N. BOOTH, OF DETROIT, MICHIGAN, ASSIGNOR TO KELSEY-HAYES WHEEL CORPORATION, OF DETROIT, MICHIGAN, A CORPORATION OF NEW YORK

APPARATUS FOR FORMING BRAKE DRUMS

Application filed March 24, 1926. Serial No. 97,065.

The invention relates to apparatus for forming brake drums and refers more particularly to presses for forming brake drums from sheet metal by a drawing operation. 5 One of the objects of the invention is to provide an apparatus for forming a mechanically true brake drum having a concentric brake flange. Another object is to provide an apparatus having means for stripping or disengaging the brake drum from the plunger without distorting the brake drum. With these as well as other objects in view the invention resides in the novel features of construction and combinations and arrangements of parts as more fully hereinafter set forth.

In the drawings:—

Figure 1 is a sectional side elevation of an apparatus embodying my invention; 20 Figure 2 is a sectional side elevation of the press forming part of the apparatus; Figure 3 is a plan view thereof with the punch removed.

Figure 4 is a perspective view of one of 25 the strippers forming part of the press;

Figures 5, 6, 7, 8 and 9 are sectional elevations showing the operation of the press;

Figure 10 is a view similar to Figure 2 and showing a modified press.

In general, the apparatus embodying my 30 invention includes the press having the bed 1 and the ram 2. The bed supports the die 3 and the ram carries the punch 4 which is adapted to cooperate with the die to draw a sheet metal blank into a brake drum.

The die comprises the die block 5 having the axial flared opening 6 and the concentric die block 7 set into the die block 5 and having the axial flared opening 8 in its upper portion and the axial cylindrical opening 9 in its lower portion, both of these die blocks resting upon the presser plate 10. These die blocks are suitably secured in place as by means of the wedge-shaped ring 11 which has a wedge-shaped inner face engaging a corresponding

wedge-shaped outer face upon the die block 5 and a cylindrical outer face engaging a corresponding face upon the annular flange 12 of the spacer 13 forming part of the bed 1. The ring 11 is held in place by means of the cap bolts 11' which are threaded into the spacer 12. The upper face of the die block 5 is preferably provided with the axial recess 14 for initially receiving the sheet metal disk when the punch 4 is elevated above the die 3. 55

The punch comprises the cylindrical body 15 rigidly secured to and depending from the ram 2 and having secured to its lower end the concentric ring 16 and a concentric plate 17 which is located between the ring 16 and the annular shoulder 18 of the body. The ring is preferably threaded upon a reduced portion at the lower end of the body. The punch also comprises the pad 19 which is in the nature of a plate and which preferably fits in the lower portion of the ring 16 so that the lower face of the pad may register with the lowermost face of the ring. 65

For the purpose of forming the steel disk into a mechanically true brake drum with a 70 concentric brake flange, I have provided the pad 20 which is concentric with the die 3 and is reciprocable within the aperture of this die. This pad is operated by air pressure and is normally located to contact with the disk 75 when the punch is elevated above the disk. This pad offers sufficient resistance to the downward movement of the punch to firmly clamp the central portion of the disk against the punch but at the same time the resistance 80 is such that the pad is moved downwardly with the punch. With this arrangement the central portion of the disk which eventually forms the web of the brake drum is held from distortion during the forming operation of 85 the brake drum so that the brake flange is mechanically true and remains concentric when the brake drum is removed from the press. In detail, the pad 20 is mounted upon the upper end of the rod 21 which extends 90

downwardly through the bed of the press and is secured to the upper intermediate and lower pistons 22, 23 and 24, respectively reciprocable within the axially aligned upper intermediate and lower cylinders 25, 26 and 27, respectively. These cylinders are carried by and depend from the bed of the press. The lower end of the upper cylinder 25 is in constant communication with the tank 28 which contains compressed air and the lower ends of the cylinders 26 and 27 are in constant communication with the tank 29 which contains compressed air at a lower pressure than the air in the tank 28. The upper end 10 of the cylinder 25 is adapted to be placed in communication with the tank 28, there being the control valve 30 in the pipe line forming the communication. The upper ends of the cylinders 26 and 27 are adapted to be placed 15 in communication with the tank 29, there being the control valve 31 in the pipe line forming this communication.

To remove the brake drum from the press without distorting the brake drum, the upper 25 pad 19 is arranged to operate as a stripper and in addition I provide a second stripper 32. The stripper 32 is arranged to take care of unequal widths of the portions of the brake flange engaged thereby and applies 30 equal force thereto in disengaging the same from the ring 16 of the punch. This stripper has the links 33 which extend upwardly through recesses 34 in the spacer communicating with the axial opening 35 in the 35 spacer, these recesses being located outside the path of travel of the punch so that the links will not interfere with the downward movement of the punch. At the upper end of each link there is a plunger 36 which extends 40 transversely of the link and is yieldably forced radially inward by means of the coil spring 37. This plunger is held in a position such that its beveled end 38 may be engaged by the brake drum flange upon downward movement thereof to force the plunger 45 outwardly during the travel of the brake drum flange past the plunger, after which the plunger is moved radially inward to engage the periphery of the ring 16 of the 50 punch above the brake drum flange. Each plunger is limited in its radial inward movement by suitable means which as shown comprises the nuts 39 threaded upon the outer end of the stem 40 and engageable with the 55 wall 41 at the outer side of the link. The lower ends of the links are pivotally connected to the arms 42 which extend radially outward from and are preferably integral with the male member 43 of a universal 60 mounting. This male member has a convex upper face which engages a concave lower face of the female member 44, this latter being secured axially in the bed 1 of the press. The male member 43 is normally held so that 65 the plungers 38 are in the same horizontal

plane by means of coil springs 45 which abut the lower face of the male member and the upper face of the plate 46, which is secured to the female member 44. Both the male and female members of the mounting as well as the plate therebeneath have axial openings of a size to permit the passage of the rod 21 therethrough and also to permit of the necessary rocking of the male member. With this arrangement it will be seen that the plungers 36 of the stripper 32 will properly engage the upper edge of the brake drum flange, regardless of the particular locations of the portions engaged and will apply equal pressure to these portions in stripping the 70 brake drum from the punch.

The upper pad 19 which cooperates with the stripper 32 in removing the brake drum from the punch is secured to the rod 47 which extends upwardly through the reduced lower end portion of the body 15 and is secured to the upper and lower pistons 48 and 49, respectively, which are reciprocable within the upper and lower cylinders 50 and 51, respectively, these cylinders being axially 85 aligned and located within the body 15. The upper and lower ends of these cylinders respectively communicate with the pipes 52 and 53 which lead to a suitable four-way valve 54 for controlling the passage of compressed air to either the upper ends or lower ends of the cylinders as well as the exhaust of the air from these ends, the arrangement being such that at substantially the time of engagement of the plungers 36 of the stripper 32 with the upper edge of the brake drum flange, the pad 19 is held from upward movement by compressed air entering the upper ends of the cylinders 50 and 51, while the body 15 of the punch continues its upward 90 movement.

The spacer 13 is provided with the radially extending slot 55 communicating with its axial opening 35 and having a width slightly greater than the diameter of the brake drum and a height slightly greater than the width of the brake drum flange so that the brake drum may be removed below the die 3.

To automatically remove the brake drum after it has been stripped, I have provided an ejector in the nature of rods 56 which slidably extend radially through the portion of the spacer opposite the slot 55, the inner ends of these rods being engageable with the brake drum flange. These rods are pivotally connected at their outer ends to the lever 57 of a bell crank arm, which is pivotally connected at 58 to the bracket 59 upon the bed 1. The other lever 60 of this bell crank arm is engageable by the dog 61 which is pivotally mounted upon the link 62, the upper end of which link is pivotally connected to the bracket 63 upon the ram 2. 64 is a suitable guide engageable with an intermediate portion of the link 62 and pivotally mounted upon the 100 105 110 115 120 125 130

bracket 65 which is secured to the bed 1. The dog 61 is arranged to positively actuate the lever 60 during the upward movement only of the link 62 and is so located upon this link that it does not actuate the lever until the 5 brake drum has been stripped and the pad 19 has been moved upwardly out of the brake drum. As shown, this dog is pivotally mounted upon the block 66 which is adjustably secured upon the link 62 and is normally held in position to engage the lever 60 or a pin thereof by means of the coil spring 67. The nose of this dog is beveled so that during the downward movement of the link 62 the 15 dog can swing while passing the lever 60, but after it has passed this lever it swings to its normal position under the influence of the spring 67 and is held from further swinging in this direction by coming into contact with a shoulder upon the block. To return the ejector rod 56 to inoperative position, I have provided the weight 68 upon the arm 69 which is fixed upon the pivot 58 of the bell crank arm.

20 In operation and with the parts in the positions shown in Figure 5 and a steel disk in place upon the die, compressed air is in the cylinders 50 and 51 below the pistons 48 and 49 to hold the pad 19 upwardly against the ring 16 upon the body 15 of the punch. Also the upper ends of the cylinders 25, 26 and 27 are in communication with the atmosphere by reason of the valves 30 and 31 opening to the atmosphere and at the same time closing 25 the communication to the tanks 28 and 29. It will thus be seen that upon downward movement of the ram and the punch the pad 20 offers a resistance to this movement resulting from the pressure of air in the cylinders 25, 26 and 27 below the pistons in these 30 cylinders so that the central portion of the steel disk is firmly clamped. When the brake drum has been drawn, as shown in Figure 6, compressed air is allowed to enter the upper ends of the cylinders 25, 26 and 27 35 above the pistons in these cylinders by reason of the valves 30 and 31 placing the tanks 28 and 29 in communication with their respective cylinders. These valves have been actuated by means of the pivoted fingers 70 and 71 upon the rod 72 which is connected to the ram 2 to be moved therewith. As a consequence, during the continued downward movement of the ram and punch, the resistance offered by the pad 20 gradually decreases until the ram and punch have reached their lowermost points, at which time the air pressure within the cylinders 25, 26 and 27 40 and on opposite sides of the pistons therein is balanced, the parts now being in the position shown in Figure 7. The pad 20 now remains stationary during the upward movement of the ram and punch and during the initial portion of this upward movement compressed air is allowed to enter the upper ends 45 of the cylinders 50 and 51 above the pistons therein and the air in these cylinders below these pistons is allowed to exhaust so that the pad 19 tends to remain stationary and cooperates with the stripper 32 to disengage 50 the brake drum from the ring 16 upon the body 15 of the punch. The entrance and exhaust of the air is controlled by the four-way valve 54, which, during this portion of the upward movement of the ram, is actuated by the finger 73 mounted upon the rod 74, which is secured to the ram, the parts being in the position shown in Figure 8. Continued upward movement of the ram then brings the finger 75 upon the rod 72, which is also secured to the ram, into position to actuate the valve 54, which then permits air to exhaust through the pipe 52 from the upper ends of the cylinders 50 and 51 and compressed air to enter the cylinders below the pistons thereby raising the pad 19 to its normal position and out of the brake drum, this 55 brake drum then resting upon the pad 20 and being in position to be engaged by the ejector rod 56 upon continued upward movement of the ram to be forced outwardly through the slot 55 in the spacer 13, the parts during this portion of the operation being in the position shown by Figure 9. During the final portion of the upward movement of the ram, the valve 30 is first actuated by the finger 76 which is mounted upon the rod 72 to place the upper end of the cylinder 25 in communication with the atmosphere thereby allowing the pad 20 to raise to its original position. Then the valve 31 is actuated by the finger 77 also upon the rod 72 to close the communication between the upper ends of the cylinders 26 and 27 with the tank 29 and to place the upper ends of these cylinders in communication with the atmosphere. With this arrangement, the pad 20 is slowly raised 60 to its original position.

65 With the modified press shown in Figure 10, the web of the brake drum is formed with reinforcing ribs and also with apertures during the drawing operation. This press is of the same general construction as the press above described. It differs, however, in the specific construction of punch and pad which have provision for forming the ribs in the web of the brake drum as well as punching apertures in this web. In detail, the pad includes the lower and upper sections 79 and 80, respectively, the central punch 81 and the series of concentric punches 82 surrounding the central punch. 83 is a ring surrounding the upper section 80 and secured to the lower section 79. The central punch 81 rests upon the lower section 79 and has its upper end extending above the adjacent surrounding portion of the upper section 80 a distance equal or slightly greater than the thickness of the brake drum web. The punches 82 have shoulders 84 which normally rest upon the lower 70 section 79.

section 79 so that the tops of these punches may register with the upper surface of the upper section 80. These punches, however, have the reduced lower ends 85 which extend downwardly through the lower section 79 and are adapted to abut the female member 86 of the universal mounting for the stripper 87. The punch 88 which is secured to the ram of the press has the cylindrical ring 89 which is 10 adapted to be threaded upon the reduced lower end portion of the hollow body 90 of this punch. The lower surface of the ring 89 is adapted to cooperate with the upper surface of the ring to firmly clamp the portion 15 of the disk or brake drum blank therebetween during the drawing of this blank. 91 is a plate rigidly secured to the ring 89 and consequently to the body of the punch, this plate being concentrically located within the lower 20 end portion of the ring 89 and having the central opening 92 of the same diameter as the central punch 81. The upper surface of the upper section 80 of the pad and the lower surface of the plate 91 and the inner portion 25 of the lower surface of the ring 89 are shaped so that these surfaces will cooperate to form the reinforcing ribs in the brake drum web.

In operation and upon downward movement of the ram, the ring 89 and plate 91 of 30 the punch secured to the ram clamp the central portion of the disk against the upper section 80 and the ring 83 of the pad below the disk. This central portion of the disk may be fashioned at this time to form the 35 ribs therein to approximate shape. Continued downward movement of the ram then draws the disk and forms the brake drum flange and at the end of the downward movement the lower section 79 of the pad comes 40 into contact with the female member 86, which is stationary, so that the web of the brake drum is bumped and the ribs therein are completely fashioned. Also during this final downward movement, the central punch 45 81 and other punches 82 form the shoulders in the brake drum web to receive the wheel hub and the rivets or other securing means, respectively. The metal sheared from the brake drum web is forced upwardly into the 50 central hole 92 of the plate 91 and into the series of surrounding holes 93 also in this plate.

To remove the sheared metal, I have provided means carried within the hollow body 55 90 of the punch which is secured to the ram. This means includes the central ejector rod 94 and the series of surrounding rods 95 which extend downwardly through the reduced lower end portion of the body and also 60 through the plate 91. These rods are yieldably forced downwardly by suitable means such as the springs 96 and 97 so that when the brake drum has been stripped from the ring 89 upon the punch body, the sheared metal is forced back against the web of the 65

brake drum and out of the plate 91 so that the press will be ready for another operation after the brake drum has been ejected therefrom and the ram and pad have returned to their original elevated positions.

70

What I claim as my invention is:

1. In a press, the combination with a die, a punch movable relative thereto for forming a brake drum or the like and a stripper including a universally movable member and elements pivotally connected to said member and engageable with the flange of the brake drum or the like for disengaging the same from said punch.

75

2. In a press, the combination with a die, of a punch movable relative thereto for forming a brake drum or the like and a stripper for disengaging the brake drum or the like including members engageable at peripheral points with an edge of the flange of the brake drum or the like and universally movable means connected to said members for equalizing the pressure exerted by said members upon the brake drum flange.

80

3. In a press, the combination with a die, of a punch movable relative thereto for forming a brake drum or the like and a stripper for disengaging the brake drum or the like including links having means engageable at peripheral points with an edge of the flange of the brake drum or the like, a stationary female member and a cooperating male member connected to said links.

85

4. In a press, the combination with a die, of a punch movable relative thereto for forming a brake drum or the like, of a stripper for disengaging the brake drum or the like including links, spring pressed plungers carried by said links and engageable at peripheral points with the free edge of the flange of the brake drum or the like, a stationary female member and a cooperating male member connected to said links.

90

5. In a press, the combination with a die, of a punch movable relative thereto for forming a brake drum or the like and a stripper for disengaging the brake drum or the like including links having means engageable at peripheral points with an edge of the flange of the brake drum or the like, a stationary female member, a cooperating male member connected to said links and means for normally retaining said male member in a predetermined position.

95

6. In a press, the combination with a die, of a punch movable relative thereto for forming a brake drum or the like, a stripper below said die for disengaging the brake drum or the like from said punch, a member supporting said die and provided with a slot therebeneath for the passage of the brake drum or the like and means for ejecting the brake drum after it has been stripped.

105

7. In a press, the combination with a die, of a punch movable relative thereto for form-

110

115

120

125

130

ing a brake drum or the like, a ram carrying said punch, a stripper for disengaging the brake drum or the like from said punch, an ejector rod engageable with the brake drum or the like after the same has been stripped to remove the same from the press, and means connected to said ram for actuating said ejector rod.

8. In a press, the combination with a die, 10 of a punch movable relative thereto for forming a brake drum or the like and means for disengaging the brake drum or the like from said punch including a pair of strippers respectively engageable with the flange and the 15 web of the brake drum or the like.

9. In a press, the combination with a die and a reciprocable punch cooperating therewith to form from a sheet metal blank a brake drum or the like, of means cooperating 20 with said punch to clamp the central portion of the blank during the movement of the punch in a direction to form the brake drum or the like, means operable to temporarily arrest said clamping means during a portion 25 of the return movement of said punch and means for disengaging the brake drum or the like from said punch during its return movement.

10. In a press, the combination with a die 30 and a vertical reciprocable punch cooperating with said die to form from a sheet metal blank a brake drum or the like, of a vertically movable pad cooperating with said punch to clamp the central portion of the 35 blank during the downward movement of said punch to form a brake drum or the like, and means for holding said pad normally against the blank, including a plurality of aligned cylinders having their lower ends 40 each in constant communication with a source of supply of fluid under pressure, pistons slideable within said cylinders and connected to said pad, and means controlling the inlet of fluid under pressure into the upper ends 45 of said cylinders, said control means operating in timed relation to the downward movement of said punch, whereby equal pressures are exerted on the upper and lower sides of said pistons when said punch and pad are 50 in their lowered positions, and means for stripping the brake drum or the like from said punch during its upward movement including a plurality of members movable transversely of the punch and engageable 55 with the flange of the brake drum or the like.

11. In a press, the combination with a die and a vertical reciprocable punch cooperating with said die to form from a sheet metal blank a brake drum or the like, of a vertically movable pad cooperating with said punch to clamp the central portion of the blank during the downward movement of said punch to form a brake drum or the like, and means for holding said pad normally against the 65 blank, including a plurality of aligned cylinders

ders having their lower ends each in constant communication with a source of supply of fluid under pressure, pistons slideable within said cylinders and connected to said pad and means controlling the inlet of fluid under pressure into the upper ends of said cylinders said control means operating in timed relation to the downward movement of said punch whereby equal pressures are exerted on the upper and lower sides of said pistons when said punch and pad are in their lowered positions, means for stripping the brake drum or the like from said punch during its upward movement and means for ejecting the brake drum or the like after it has been stripped including a rod reciprocable transversely of the punch and engageable with the brake drum.

12. In a press, the combination with a die, 85 of a vertically movable punch cooperating with said die to form a brake drum or the like, said punch including a member having a cylindrical surface and a relatively movable pad engageable with the web of the brake drum or the like, a pad cooperating with said punch to clamp the central portion of the blank during the downward movement of said punch to form the brake drum, pressure operated means reciprocable transversely of the punch for controlling the movements of said pads, means for ejecting the brake drum or the like and ram carrying said punch and controlling the operation of said pads and ejecting means.

13. In a press, the combination with a die, 100 of a punch movable relative thereto for forming a brake drum or the like, of a stripper for disengaging the brake drum or the like including a plurality of independent links, and spring influenced plungers carried by said links and engageable at peripheral points with the free edge of the flange of the brake drum or the like.

14. In a press, the combination with a die, 110 of a punch movable relative thereto for forming a brake drum or the like, a stripper engageable with the flange of the brake drum or the like and a second stripper cooperating with the stripper aforesaid and movable by fluid pressure into engagement with the web of the brake drum to disengage the latter from the punch.

15. In a press, the combination with a die, 120 of a punch movable relative thereto for forming a brake drum and the like, means engageable with the brake drum and the like for disengaging the same from the punch, and a rigid evener member connected to the means aforesaid for equalizing the pressure exerted by said means upon said brake drum or the like.

16. In a press, the combination with a die, 130 of a punch movable relative thereto for forming a brake drum and the like, a stripper including a universally movable member, and

elements connected to said member and having portions movable relative thereto for engaging the brake drum.

17. In a press, the combination with a die, 5 of a punch movable relative thereto for forming a brake drum and the like, members engageable with the brake drum for stripping the latter from the punch, and universally movable means connected to said members for 10 equalizing the pressure exerted by the latter upon the brake drums.

In testimony whereof I affix my signature.
WILLIAM N. BOOTH.
